UNITED STATES PATENT OFFICE.

FRITZ B. ERNST, OF CHICAGO, ILLINOIS, ASSIGNOR TO AMERICAN STEEL FOUNDRIES, OF CHICAGO, ILLINOIS, A CORPORATION OF NEW JERSEY.

RAILWAY-CAR TRUCK.

Application filed January 6, 1923. Serial No. 610,978.

To all whom it may concern:

Be it known that I, FRITZ B. ERNST, a citizen of the United States, residing at Chicago, in the county of Cook and State of

5 Illinois, have invented certain new and useful Improvements in a Railway-Car Truck, of which the following is a specification.

This invention relates to a railway car truck.

10 As is well known, in recent years the carrying capacity of cars has been greatly increased. As a result thereof the question of providing spring capacity has become important. Considering the matter of springs alone it may be said that any number of springs and any grouping of such springs may be used. However in the design of trucks other factors must be given serious consideration such, for example, as a short 15 wheel base which of necessity means a relatively short side frame. Accordingly, with a side frame of limited length and also taking into consideration the limited clearance for the movement of the brake heads and 20 beams, the question of increasing the spring capacity of the truck is somewhat involved, especially where it is desired to place all of the springs between the bolster columns.

25 Therefore, one object of this invention is 30 to increase the spring capacity of railway car trucks without increasing the length of the side frame and wheel base and at the same time providing all of the required clearances.

35 Another object is to provide a side frame and a high capacity spring grouping between the bolster columns thereof with the longitudinal distance between said bolster columns reduced to a minimum.

40 Another object is to provide a high capacity truck adapted to meet the various requirements of service conditions.

45 These and other objects are accomplished by means of the arrangement disclosed on the accompanying sheet of drawings, in which—

50 Figure 1 is a fragmentary side elevation of a railway car truck embodying my invention;

55 Figure 2 is an enlarged sectional view taken in the plane of line 2—2 of Figure 1; and

Figure 3 is an enlarged sectional view taken in the plane of line 3—3 of Figure 1.

55 The various novel features of the inven-

tion will be apparent from the following description and drawings and will be particularly pointed out in the appended claims.

Referring to the figures of the drawings 60 it will be noted that this invention is illustrated in connection with a railway car truck including a side frame 10 which in this particular instance, although not necessarily so, is a single piece structure, that is, 65 the compression member 11, tension member 12 and bolster columns 13 are integrally formed. The tension member 12 between the bolster columns 13 is provided with six 70 spring seats, two 14 of which are located on the transverse center of the side frame and at a lower level than the other four spring seats, two 15 of which are located on one side of the spring seats 14 and the other two 16 of which are located on the other side 75 of the central spring seats 14. Preferably the spring seats 15 and 16 are on the same level and integrally formed with the tension member 12. Two transversely aligned 80 springs 17 occupy the spring seats 14, and similarly transversely aligned springs 18 occupy the spring seats 15 and transversely aligned springs 19 occupy the spring seats 16. It is seen, therefore, that six springs 85 are seated on the tension member between the bolster column 13, there being two longitudinal rows of springs of three each offset with respect to the longitudinal center of the side frame, the two intermediate springs 17 being on a lower level than the 90 springs 18 and 19, whereby the longitudinal distance between the bolster columns 13 may be reduced to a minimum where six springs are used and whereby the downwardly converging portions of the tension 95 member 12 substantially meet at a point below the intermediate springs 17.

The side frames, only one of which is shown, may be connected either by a spring plank or by a tie rod. If a spring plank 100 is to be used, one of two arrangements are suggested herein. One arrangement is to provide but a single narrow spring plank 20, preferably channel shaped in section, upon which only the intermediate springs 17 are seated, it being noted that the spring plank fits in between the vertical side walls 21 of the outer spring seats 15 and 16. By providing this narrow spring plank, sufficient clearance is provided for the inward 105 110

movement of the brake heads 22 or brake beams or both. In another arrangement a spring plank 23 is provided upon which the four outer springs 18 and 19 are seated, said 5 spring plank having an opening through which the intermediate springs 17 extend. Although the spring plank 23 is relatively wide it is also located on a higher plane than the spring plank 20 so that a sufficient clearance is provided for the free movement of 10 the brake heads 22. It will be understood that only one of the spring planks is used at a time.

The bolster 24 rests upon the springs and 15 more particularly, transverse webs 25, forming the ceiling of spring pockets 26 in the bolster, rest upon the four outer springs 18 and 19, while the lower intermediate wall portion 27 of the bolster rests upon the intermediate springs 17. The bolster at its ends has vertical walls 28, 29, 30 and 31 which 20 form the outer spring pockets. The bolster and its guides cooperate to guide the former in its vertical movements.

25 In view of the fact that the longitudinal distance or the beam space which the intermediate springs 17 occupy, is greatly reduced, the depth thereof also may be reduced, thereby reducing the weight of the 30 side frame at that portion. Also because of this particular spring arrangement, the converging side elements of the tension member 12 may be reduced in length thereby reducing the total weight of the side frame. This spring arrangement generally 35 not only provides for increased spring capacity, but does so without increasing the length, weight and cost of the side frame and without interfering with the clearances 40 for the proper movements of the brake mechanism.

It is my intention to cover all modifications of the invention falling within the spirit and scope of the following claims.

45 I claim:

1. In a railway car truck, the combination of a side frame having bolster columns and 50 six spring seats therebetween, two of said spring seats being below the other four spring seats, whereby the spring capacity of the truck may be increased without increasing the length of the side frame.

2. In a railway car truck, the combination of a side frame having bolster columns and 55 six spring seats therebetween, two intermediate spring seats being below two spring seats

on either side thereof whereby the spring capacity of the truck may be increased and at the same time minimizing the longitudinal distance between said bolster columns where 60 six springs are used.

3. In a railway car truck, the combination of a side frame having bolster columns and six spring seats on the tension member therebetween, two of said springs being centrally arranged with respect to the other four spring seats and being at a lower level with respect thereto, whereby the converging portions of the tension member meet substantially at a point below the intermediate 70 springs, minimizing the longitudinal distance between the bolster columns.

4. In a railway car truck, the combination of a side frame including a tension member having spring seats at different levels, two 75 intermediate springs being seated on the spring seats at a lower level and the other four springs being seated on spring seats at a higher level, and a spring plank associated with certain of said springs without 80 interfering with movements of the brake mechanism.

5. In a railway car truck, the combination of a side frame having a tension member with six spring seats, certain of said spring 85 seats being on different levels, two intermediate springs located on the lower seats and four springs located on the other seats, and a bolster seated on said springs, said bolster having pockets the ceiling walls of 90 which rest upon the outer springs.

6. In a railway car truck, the combination of a side frame having bolster columns and more than four spring seats therebetween and out of vertical alignment with respect to 95 each other, one of said spring seats being on a lower level than four others, whereby the spring capacity of the truck may be increased without increasing the length of the side frame.

7. In a railway car truck, the combination of a side frame having more than four spring seats and out of vertical alignment with respect to each other, one of said 100 spring seats being on a lower level than four others, whereby the spring capacity of the truck is increased and at the same time minimizing the length of the side frame.

Signed at Chicago, Illinois, this 4th day of January, 1923.

FRITZ B. ERNST.
